Primary Examiner—M. N. Pandozzi*(74) Attorney, Agent, or Firm*—W. Scott Carson**(57) CLAIM**

The ornamental design for a combined coconut-shaped drink container and coin bank, as shown and described.

DESCRIPTION

FIG. 1 is a top perspective view of a combined coconut-shaped drink container and coin bank showing my new design.

FIG. 2 is a front elevational view thereof.

FIG. 3 is a right side elevational view thereof.

FIG. 4 is a left side elevational view thereof.

FIG. 5 is a rear elevational view thereof.

FIG. 6 is a top plan view thereof.

FIG. 7 is a bottom plan view thereof.

FIG. 8 is a top perspective view of a combined coconut-shaped drink container and coin bank showing my new design showing a second embodiment of my new design.

FIG. 9 is a front elevational view thereof. The straw shown in dotted lines forms no part of my design.

FIG. 10 is a right side elevational view thereof.

FIG. 11 is a left side elevational view thereof.

FIG. 12 is a rear elevational view thereof.

FIG. 13 is a top plan view thereof; and,

FIG. 14 is a bottom plan view thereof.

The broken lines in the drawings are for illustrative purposes only and form no part of the claimed design.
